UNITED STATES PATENT OFFICE.

ROBERT W. REID, JR., OF BROOKLYN, NEW YORK.

DESIGN FOR A VALVE-CASING.

50,631.

Specification for Design.

Patented Apr. 17, 1917.

Application filed February 3, 1917. Serial No. 146,532. Term of patent 14 years.

To all whom it may concern:

Be it known that I, ROBERT W. REID, Jr., a citizen of the United States, residing in Brooklyn, in the county of Kings and State of New York, have invented a new, original, and ornamental Design for a Valve-Casing, of which the following is a specification, reference being had to the accompanying drawing, forming part thereof, in which—

Figure 1 represents a perspective view of a valve casing embodying this design.

Fig. 2 is a top view of the same.

I claim:

The ornamental design for a valve casing as shown.

ROBERT W. REID, JR.
